UNITED STATES PATENT OFFICE.

LESTER H. HOPEWELL, OF BROOKLYN, NEW YORK.

APPARATUS FOR PREVENTING GRADE-CROSSING ACCIDENTS.

Application filed January 16, 1926. Serial No. 81,664.

This invention relates to apparatus adapted to be inserted in a roadway or highway to prevent grade-crossing accidents.

It is an object of this invention to provide 5 an apparatus which is adapted to prevent vehicles from approaching railroad tracks at times when trains are crossing or about to cross the intersection of a track with a roadway and thus to prevent collisions and other 10 dangerous grade-crossing accidents.

It is a further object of the invention to provide means by which the apparatus may be placed in operative condition when desired and to provide means by which the said 15 apparatus may be placed in inoperative condition so that the roadway may be ordinarily used by vehicles in the usual manner.

Other objects and advantages of the invention will appear hereinafter.

20 A preferred embodiment of the invention is illustrated in the accompanying drawings, in which,

Figure 1 is a diagrammatic view showing the intersection of a roadway with a railroad 25 track, the apparatus of the invention being inserted in the roadway.

Figure 2 is a diagrammatic view showing the electrical connections.

Figures 3 and 4 are detailed sectional 30 views showing the apparatus in inoperative and operative positions respectively.

Fig. 5 is a detail of the ratchet mechanism.

Referring to the drawings, a substantially flat plate 1 is inserted in the roadway 2 at 35 a point near the intersection of the roadway with the railroad track, the said plate being arranged to lie substantially flush with the surface of the roadway. The plate 1 is provided with a multiplicity of apertures 3 40 through which project the rollers 4 which for convenience may be carried in a frame 5, the said rollers being mounted coincidently with said apertures in order that when the apparatus is in the position illustrated in 45 Figure 4 each of the apertures 3 will have part of the outside periphery of one of the rollers 4 projecting therethrough.

The rollers are located sufficiently closely together that the tire or wheel of the ordinary vehicle is supported by the rollers when 50 in the position illustrated in Figure 4 without touching the plate 1. The rollers are

mounted to rotate freely in a counter-clockwise direction and it will be observed that due to this provision the vehicle is unable 55 to obtain sufficient traction to move it forwardly along the roadway toward the track. In other words, if the vehicle is moving forwardly under power, as soon as the rear wheels come in contact with the rollers 60 4 they are permitted to spin freely, and the vehicle may be quickly brought to a stop due to the jolting against the projecting rollers or by the barrier 5' hereinafter described.

Each of the rollers is provided with a 65 ratchet 6, however, which prevents rotation in a clockwise direction, in order that if the vehicle is approaching the track and is not under power, it may be brought to a stop by 70 the application of the brakes in the usual manner.

If desired, the frame 5 may also be provided with a barrier 5' which may be formed integrally therewith or attached rigidly 75 thereto. When the frame is in the position shown in Figure 4 the barrier 5' projects through the plate 1 and offers a substantial obstacle to an oncoming vehicle which has failed to be stopped either by loss of traction or by the application of brakes. 80

The frame 5 is mounted in such manner that it may be lowered from the position shown in Figure 4 to the position shown in Figure 3, the rollers 4 and the barrier 5' in the latter case being removed from the apertures in order to provide a substantially flat surface over which vehicles may pass in the usual manner, the apertures 3 being small enough to prevent vehicle wheels from dropping therein. In order that the frame may be raised and lowered conveniently, the ends of the frame are attached to the cables 7 and 8, the cable 7 passing over the pulley 9 and under pulley 10 to the reel 11, and the cable 8 passing over the pulley 12 and under pulleys 13 and 14 to the reel 11. If desired, the counterweights 15 and 15' may be provided to balance the weight 85 of the platform and the rollers mounted thereon, and rails 18 may be provided to 90 guide the platform during its travel and to hold it stationary when in operative position. 95

The reel 11 may be driven by the electric motor 16, suitable driving connections such 100

as the bevel gears 17 being provided between the motor and reel. The motor 16 may preferably be of a reversible type capable of operation in one direction to raise the platform 5 and in an opposite direction to lower the same.

It may be desirable that the apparatus be automatically controlled by the train and accordingly means are provided which may 10 be operated by the train in approaching or leaving the intersection to raise or lower the platform as desired.

The apparatus is normally maintained in the position shown in Figure 3, the frame 15 being lowered so that the vehicles may pass along the road without interference. When a train approaches the intersection, however, in a direction indicated by the arrow in Figure 1 the wheels of the train engage 20 the shoe 21 causing a circuit to be made which drives the motor 16 in a direction to raise the platform 5. The shoe 21 may be conveniently mounted in a block 22, and may be provided with contacts 23 to engage 25 the fixed contacts 24 which may be connected to a suitable source of current by leads 25.

If desired, the electro-magnets 26 may be embedded in the block 22, said electro-magnets 30 being connected to the circuit made by the shoe in order that as soon as the circuit is completed the electro-magnets may be energized to hold the shoe in position to complete the circuit. The motor 16 is thus 35 driven to rotate the reel 11 to raise the platform 5.

In order that upward movement of the platform 5 may be stopped when the rollers 4 are in proper operative position, the shut-off switch 30 is mounted on the frame 5, 40 consisting of a plunger 31 which is adapted to bridge the contacts 32 to complete the circuit. When the platform 5 has been raised to its proper operative position, however, the end of the plunger 31 engages the 45 under side of the plate 1 and breaks the circuit causing the motor to stop. At the same time the electro-magnets are de-energized and the shoe 21 is returned to its original 50 position under the influence of the springs 21'.

After the train has passed the intersection of the track and the roadway it is desirable to lower the platform 5 to withdraw the rollers 4 from the apertures and 55 means are provided for accomplishing this purpose and such means may also preferably be controlled by the train.

Accordingly, after the train has passed 60 the intersection, the wheels may engage the shoe 35 mounted in the block 36 and which is constructed and operated in a manner similar to the shoe 21. Movement of the shoe caused by engagement with the wheels 65 of the train causes the contacts 37 to engage

contacts 38 to complete a circuit to cause reverse rotation of the motor 16 to lower the platform 5. As in the case of the shoe 21 electro-magnets 39 are provided and are energized when the circuit is made to hold 70 the shoe in position to complete the circuit.

In order that lowering movement of the platform 5 may be stopped at the proper time, however, the shut-off switch 40 is provided having a plunger 41 which normally 75 bridges the contacts 42 to complete the circuit. When the platform is lowered to inoperative position the under side of the platform engages the plunger 41 causing the circuit to be broken thus stopping the motor 80 16 and preventing further lowering of the platform. At the same time the electro-magnets 39 are de-energized and the shoe 35 returns to normal position.

It will be observed that when the frame 85 5 is in the position shown in Figure 4, the combined effect of loss of traction due to the freely revolving rollers and the severe jolting which would be caused by the projection of the rollers through the plate 1 would 90 quickly serve to bring the vehicle to a stop even though the operator failed to apply the brakes. In the event that the vehicle is driven at an excessive rate of speed, the barrier 5' serves to positively stop the vehicle 95 if all other means fail.

It will be understood that the invention may be variously modified and embodied within the scope of the subjoined claims.

I claim as my invention:

100

1. An apparatus for insertion in a roadway, comprising, in combination, a plate having a plurality of apertures therein, means to support a plurality of rollers mounted coincidently with said apertures, 105 and means to raise said supporting means to cause said rollers to project through said apertures.

2. An apparatus for insertion in a roadway, comprising, in combination, a plate 110 having a plurality of apertures therein, means to support a plurality of rollers mounted coincidently with said apertures, and means to raise and lower said supporting means to cause said rollers to project 115 through said apertures or to disappear beneath said plate.

3. An apparatus for insertion in a roadway, comprising, in combination, a plate having a plurality of apertures therein, 120 means to support a plurality of rollers mounted coincidently with said apertures, and means to prevent rotation of said rollers in one direction.

4. An apparatus for insertion in a roadway, comprising, in combination, a plate having a plurality of apertures therein, and 125 means to support a plurality of rollers mounted coincidently with said apertures and adapted to project therethrough.

130

5. An apparatus for insertion in a road-way near the intersection thereof with a railway track, comprising, in combination, means presenting a surface to the wheels of a vehicle approaching said intersection, said surface being freely movable in a direction away from said intersection, and means to

oppose movement of said surface in a direction toward said intersection.

In testimony whereof, I have signed my ¹⁰ name to this specification this 15th day of January 1926.

LESTER H. HOPEWELL.
